UNITED STATES PATENT OFFICE.

CHARLES A. BARKER, OF NEW YORK, AND FREDERICK LEVEASON GREEN,
OF LONG ISLAND CITY, NEW YORK.

DESIGN FOR A BADGE.

SPECIFICATION forming part of Design No. 24,938, dated November 26, 1895.

Application filed September 24, 1895. Serial No. 563,558. Term of patent 3½ years.

To all whom it may concern:

Be it known that we, CHARLES A. BARKER, a subject of the Queen of Great Britain, residing in New York city and county, and 5 FREDERICK LEVEASON GREEN, a citizen of the United States, residing at Long Island City, in the county of Queens, State of New York, have invented and produced a new and original Design for a Badge, of which the following is a specification, reference being had to the accompanying drawings, forming a part thereof, in which—

Figure 1 is a front elevation of the badge, and Fig. 2 is a vertical section taken substantially through the center.

The design consists in the simulation of an elephant in profile and in front view and in forming the back of the elephant-like figure in substantially straight lines, the front por-

tion having a convexed appearance, and, in 20 addition to the elephant-like figure, of a spur-like object, which extends from the back of the elephant figure and apparently forms a support therefor.

We claim—

The design for a badge substantially as herein shown and described.

CHARLES A. BARKER.
FREDERICK LEVEASON GREEN.
